DESIGN FOR A SACHET BAG OR SIMILAR ARTICLE

Otto S. Garry, New York, N. Y.

Application March 6, 1940, Serial No. 90,713

Term of patent 3½ years

To all whom it may concern:

Be it known that I, Otto S. Garry, a citizen of the United States, residing in New York city, in the county of New York and State of New York, have invented a new, original, and ornamental Design for a Sachet Bag or Similar Article, of which the following is a specification, reference being had to the accompanying drawing, forming part thereof.

Fig. 1 is a front elevational view of a sachet bag showing my design;

Fig. 2 is a rear elevational view of Fig. 1, and Fig. 3 is a plan view thereof.

I claim:

The ornamental design for a sachet bag or similar article, substantially as shown.

OTTO S. GARRY.
